UNITED STATES PATENT OFFICE

EDMUND T. FLEWELLING, JR., OF HIGHLAND PARK, ILLINOIS, ASSIGNOR TO BUELL MANUFACTURING CO., OF CHICAGO, ILLINOIS, A CORPORATION OF ILLINOIS

RECEIVING CIRCUIT

Application filed September 25, 1924. Serial No. 739,771.

This invention relates to radio receiving circuits, and among other objects aims to provide an improved receiving system for either damped or undamped waves which, 5 without an external heterodyne, may largely amplify the incoming signal.

The invention may be understood by reference to the illustrative embodiments shown diagrammatically in the accompanying drawings, in which:

Fig. 1 is a diagram of a system embodying the invention;

Fig. 2 is a diagram of a modified system; and

Fig. 3 is a further modification.

It is to be understood that the illustrative forms shown in the drawings are simply various embodiments of the invention, and that in the following explanation, the described details of arrangement and organization are merely exemplary.

In the regenerative feed back system employing a grid condenser, it is well known that under proper adjustment for reception 25 of signals, means must be provided to allow the accumulated charge upon the grid of the vacuum tube to leak off so that it may be free to receive the next incoming signal. It has been observed that by adjustment of a 30 suitable variable high resistance (used as a grid leak), the grid may be freed almost at will. In such a regenerative receiver, as the grid is blocked by an accumulated charge and freed by leakage of the charge through 35 the grid leak, it will be noticed at some adjustment of the grid leak that one will hear in the telephone receivers a single clicking sound and that this sound by adjustment of the grid leak may be caused to occur oftener 40 or less often than once every second. As this frequency is increased by adjustment of the system it has been found that the rapidity of occurrence of the clicks creates a low musical note increasing in pitch as adjustment 45 is continued until it is so high as to pass beyond the limits of human hearing.

If a regenerative receiver is adjusted to the point of oscillation (when amplification is greatest), and the grid is alternately 50 blocked and freed by adjustment of the grid

leak, this action may be properly timed so as not to destroy the incoming signal. For best results, the leakage from the grid should be confined to the grid leak; hence a "hard" or high vacuum tube should be used, 55 as will be understood.

In Fig. 1 is shown diagrammatically a receiving circuit which gives excellent amplification under the above conditions. The circuit includes variable inductances 5, 6, 60 a high vacuum tube 7 having plate 8, grid 9 and filament 10, the telephone receiver or equivalent 11, battery 12 in circuit with the telephone, filament heating battery 13, and adjustable resistance 14 for varying the filament current. The plate 8 obtains its potential from battery 12. As is customary, 65 capacity in the form of variable condenser 15 is placed in the receiving circuit. The grid condenser 16 has an adjustable high 70 resistance or grid leak 17 shunted across it, thus permitting freeing of the grid at any 75 desired rate.

In my improved receiving set, shown in Fig. 1, a group of three condensers is placed 75 in the circuit, two of the condensers 18 and 19 being fixed and connected to the filament end of the inductance, the third condenser 20 being shunted across the other two and preferably having a shunted variable resistance 21. With the circuit shown, it has been found that, within certain limits, the larger the capacity of the condensers 18, 19 and 20, the greater the amplification; the condenser capacity which gives the best 80 results generally being about 0.006 microfarad for each condenser. It was further found that if condenser 20 is of the correct capacity, it is generally unnecessary to vary both the grid leak and the variable resistance 21, in tuning the circuit. Nor are considerable adjustments in the grid leak 85 usually necessary for large changes in wave length.

In actual use of the system shown in 95 Fig. 1, any signals received are enormously amplified; in fact, audible signals are receivable with the circuit without the use of any other antenna or ground than that afforded by the wiring and component parts 100

of the receiving system itself. However, the system may, of course, be used with an ordinary grounded antenna; or it will satisfactorily receive signals if used with a loop aerial, with an antenna without a ground, or with a ground without an antenna. Excellent reception has been secured by use of an antenna with no ground.

In Fig. 2 there is shown much the same circuit as in Fig. 1, except that the inductances 5^a, 6^a are close coupled and are not variable, and the condensers 19 and 20 and the variable resistance 21 are omitted, the condenser 18, however, being retained. This circuit has not been found to give results as excellent as the circuit of Fig. 1, but it works satisfactorily.

The arrangement in Fig. 3 is precisely the same as that of Fig. 2, except for the addition of a variable resistance 22 in the shunt 23.

Obviously, the present invention is not restricted to the particular embodiments thereof herein shown and described. Moreover, it is not indispensable that all the features of the invention be used conjointly since they may be employed advantageously in various combinations and subcombinations as defined in the claims.

Having described my invention what I claim is:

1. A receiving set comprising a receiving circuit, a grid circuit containing not less than two capacities in series between the grid and filament, and a plate circuit containing two reactances in series between the plate and filament, one of said reactances being the sound producing means and the other constituting an inductive feed-back means, a shunt connection from a point in the plate circuit separated from the plate by one of said reactances and from the filament by the other of said reactances, said shunt connection being branched to tap the grid circuit on opposite sides of one of said grid circuit capacities, a condenser in one branch of said shunt, and means for delivering incoming signals to said grid circuit.

2. A receiving set comprising a grid circuit containing not less than two capacities in series between the grid and filament, and a plate circuit containing two reactances in series between the plate and filament, a shunt connection from a point in the plate circuit separated from the plate by one of said reactances and from the filament by the other of said reactances, to a point in the grid circuit separated from the filament by one of said capacities and from the grid by the other of said capacities, and means for delivering incoming signals to said grid circuit.

3. A receiving set comprising a grid circuit containing not less than two capacities in series between the grid and filament, and a plate circuit containing two reactances in series between the plate and filament, one of said reactances being the sound producing means and the other constituting a feed-back means, a shunt connection from a point in the plate circuit separated from the plate by one of said reactances and from the filament by the other of said reactances, to a point in the grid circuit separated from the filament by one of said capacities and from the grid by the other of said capacities, and means for delivering incoming signals to said grid circuit.

4. A receiving set comprising a grid circuit containing not less than two capacities in series between the grid and filament, and a plate circuit containing two reactances in series between the plate and filament, one of said reactances being the sound producing means and the other constituting an inductive feed-back means, a shunt connection from a point in the plate circuit separated from the plate by one of said reactances and from the filament by the other of said reactances, said shunt connection being branched to tap the grid circuit on opposite sides of one of said grid circuit capacities, a condenser in one branch of said shunt, and means for delivering incoming signals to said grid circuit.

5. A receiving set comprising a grid circuit containing not less than two capacities in series between the grid and filament, and a plate circuit containing two inductive reactances in series between the plate and filament, a shunt connection from a point in the plate circuit separated from the plate by one of said reactances and from the filament by the other of said reactances, said shunt connection being branched to tap the grid circuit on opposite sides of one of said grid circuit capacities, a condenser in each branch of said shunt, and means for delivering incoming signals to said grid circuit.

6. A receiving set comprising a grid circuit containing not less than two capacities in series between the grid and filament, and a plate circuit containing two reactances in series between the plate and filament, a shunt connection from a point in the plate circuit separated from the plate by one of said reactances and from the filament by the other of said reactances, to a point in the grid circuit, and means for delivering incoming signals to said grid circuit.

In testimony whereof, I have signed my name to this specification.

EDMUND T. FLEWELLING, JR.
